UNITED STATES PATENT OFFICE

96,356

DESIGN FOR A FEMALE CHILD FIGURE OR SIMILAR ARTICLE

Charles A. Van Evera, Berkeley, Calif., assignor to Standard Stations, Inc., San Francisco,
Calif., a corporation of Delaware

Application April 30, 1935, Serial No. 56,630

Term of patent 14 years

To all whom it may concern:

Be it known that I, Charles A. Van Evera, a citizen of the United States, residing in the city of Berkeley, county of Alameda, State of California, have invented a new, original and ornamental Design for a Female Child Figure or Similar Article, of which the following is a specification, reference being had to the accompanying drawing, forming part thereof.

In the drawing:

I claim:

The ornamental design for a female child figure or similar article, substantially as shown.

CHARLES A. VAN EVERA.
